PAPER WEIGHT OR SIMILAR ARTICLE

William G. Kurtz, Jr., East Rockaway, N. Y.

Application November 18, 1954, Serial No. 33,153

Term of patent 14 years

(Cl. D74—12)

The figure is a perspective view of a paper weight or similar article showing my new design.

The ornamentation shown on the two vertical sides of the base portion of the figure is repeated on the two vertical sides not shown.

This is a continuation-in-part of my design application Serial No. D-24,108 filed March 19, 1953 and now abandoned.

I claim:

The ornamental design for a paper weight or similar article, as shown and described.
